DESIGN FOR A FILM REEL

Jack M. Goldmann, New York, N. Y., assignor to
Amereel Corporation, New York, N. Y., a corporation of New York

Application April 3, 1947, Serial No. 138,131

Term of patent 3½ years

(Cl. D61—1)

To all whom it may concern:

Be it known that I, Jack M. Goldmann, a citizen of the United States, residing at New York city, in the county of New York and State of New York, have invented a new, original, and ornamental Design for a Film Reel, of which the following is a specification, reference being had to the accompanying drawing, forming part thereof.

In the drawing

Fig. 1 is a side view of a film reel, showing my new design, and Fig. 2 is a front view thereof.

The opposite side of the film reel shown in Fig. 1 is identical in design to that illustrated in said figure.

I claim:

The ornamental design for a film reel, substantially as shown and described.

JACK M. GOLDMANN.
